UNITED STATES PATENT OFFICE.

BENJAMIN WOLHAUPTER, OF NEW ROCHELLE, NEW YORK.

RAIL-ANCHOR.

1,368,314.

Specification of Letters Patent. Patented Feb. 15, 1921.

Application filed July 14, 1920. Serial No. 396,073.

To all whom it may concern:

Be it known that I, BENJAMIN WOLHAUPTER, citizen of the United States, residing at New Rochelle, in the county of Westchester 5 and State of New York, have invented certain new and useful Improvements in Rail-Anchors, of which the following is a specification.

This invention relates to an improvement 10 in that class of rail anchors intended to remain operative and effective at all times regardless of the expansion and contraction of the rails due to temperature changes.

A primary object is to provide a rail 15 anchor susceptible of embodiment in a variety of forms which can be inexpensively and readily made by ordinary processes, and which may be permanently affixed to the rail by simple welding operations, while at 20 the same time requiring only a fixed abutment, such as the tie, to render the anchor operative and effective.

For illustrative purposes certain preferred 25 and practical embodiments are shown in the drawings, in which:—

Figure 1 is a side elevation of a part of a rail having welded thereto a rail anchoring element, in accordance with the present invention.

Fig. 2 is a cross sectional view on the line 2—2 of Fig. 1 showing the attached anchoring element in elevation.

Fig. 3 is a view similar to Fig. 1 illustrating another form of rail anchoring member which co-operates with the tie and is permanently welded onto the upper side of the rail flange.

Fig. 4 is a top plan view of the form of construction shown in Fig. 3.

Fig. 5 is a top plan view illustrating another modification in the form of the rail anchoring element and also as to the form of the weld.

Fig. 6 is a detail cross sectional view illustrating more particularly the form and character of weld that may be employed for permanently uniting the anchoring element to the flange of the rail.

Like references designate corresponding 50 parts throughout the several figures of the drawings.

The present invention contemplates the use of an anchoring element of a simple form of construction which will lend itself readily to 55 a mechanical or electrical welding operation to thereby permanently and rigidly secure

the same to the rail in such a manner and position that it will engage the tie or a tie plate as an abutment. This will provide a complete anticreeper or rail check device, 60 thoroughly effective in its function of checking longitudinal movement of the rail, and not subject to relative displacement due to expansion and contraction of the rails or to vibration of the rail and track by the traffic 65 passing over it.

It is preferable that the anchoring element be of a type that can be readily manufactured by ordinary rolling, bending and punching operations, and by way of exemplifying the general scope of the invention, there are shown in the drawings several forms of anchoring elements possessing the same structural characteristics and functions, and all intended to be permanently 70 united to and with the rail in substantially 75 the same manner, that is by a special form and location of weld.

Referring first to the illustration of Figs. 1 and 2 of the drawings. There is shown 80 in these figures a rail anchoring element designated by the reference letter A and of the type generally known as a "rail clip." This rail clip is usually constructed of a single piece of steel bent to provide the upper 85 and lower gripping jaws 1 and 2 respectively. These jaws are divergently related to provide there-between a tapering socket 3 which receives the tapering flange of the rail, and it will also be noted that the socket 90 of the clip is of a sufficient depth to provide the necessary clearance and adjustment for the clip to be initially driven to a firm seating position on the rail flange. Thus, the clip form of anchoring element A provides 95 a device which snugly fits the rail flange and firmly engages both the upper and lower sides of the flange, thereby having an extended bearing engagement with the flange and becoming a solid and substantial part 100 of the rail when permanently fastened thereto.

According to the present invention the permanent fastening of the anchoring element to the flange of the rail is preferably 105 effected by a welding operation which will so unite and secure the element to the rail as to provide a rigid part of sufficient stability to effectually resist longitudinal movement of the rail when the said anchoring element is 110 engaged with an abutment such as the tie or the tie plate on the tie. A distinctive

feature of the invention, in the foregoing connection, is that of providing the rail-flange engaging part of the anchoring element with a welding hole 4. This welding hole 5 may be drilled or punched in the element, at one or more places, and the inner edges of said hole utilized for welding with an electric or oxyacetylene weld. It will also be apparent that the welding hole 10 presents a desirable form of construction because such weld is located in the body portion of the anchor and where it will hold more substantially than at the outer edges. Furthermore, the "fillet" welds do 15 not form protuberances or objectionable fins about or on the anchor when inclosed in a hole, or a composition 5 such as "thermit" may be placed in said hole which will form a pocket or receptacle for the same. This 20 will provide a stable and rigid connection serving in effect as a stud, between the anchoring element and the rail flange capable of withstanding the force or pressure imposed thereon by the tendency of the rail 25 to "run" or creep.

In the form of construction shown in Figs. 1 and 2, both the upper and lower jaws of the clip may be advantageously welded to the rail flange, and the lower jaw of the clip 30 will also engage against the tie or other abutment to resist the tendency of the rail to creep. This is a very strong, though simple, device and will be quite effectual for the intended purposes, but by way of illustrating the range of modification that may 35 be resorted to in carrying forward the invention, there is shown in Figs. 3 and 4 of the drawings a rail anchoring element essentially comprising a depending body plate 40 6, extending below the edge of the rail flange, and formed with an inwardly bent or deflected bearing ear 7 adapted to flatly engage the fixed abutment such as the tie. The bearing ear 7 is shown disposed entirely 45 beneath the rail bottom and presents a relatively wide surface, of rectangular or other form, which affords a very substantial contact or bearing member for engaging with the tie or other abutment. In addition to the inwardly projecting bearing ear the depending body plate 6 is formed at its upper edge with an inturned holding member 8 adapted to overlie the rail flange and flatly engage the top surface of the latter. 50 This holding member 8 is provided therein with a welding hole 9 in which the welding operation is carried out to produce the circular weld 10 which rigidly unites the anchor element to the rail flange.

60 A further modification of the essential features of the invention is suggested in Fig. 5 of the drawings which represents a rail anchoring element of substantially the same construction as the element shown in Fig. 3 of the drawings with the exception

of the bearing ear designated by the numeral 7^a which is turned outwardly as shown in Fig. 5 instead of inwardly as shown in Fig. 3. Also, as shown in Fig. 5 of the drawings a plurality of the welding holes 9 70 may be employed if it is desired to increase the area or extent of the welded union between the anchoring element and the rail flange. And, in Fig. 6 there is shown more clearly how the welding operation may be 75 conveniently performed within the welding hole by the electric or oxy-acetylene processes with the result of producing an annular welding bond between the rail flange and the anchoring element. 80

From the foregoing it is believed that the invention will be readily understood without further description, and it will be noted that in so far as the specific disclosure of Figs. 1 and 2 is concerned the present application is a continuation in part of the parent application filed August 15, 1916, Serial No. 115,030. 85

I claim:

1. The combination with a rail and its 90 support, of an anchor body having a member beneath the rail base to engage said support, and another member engaging the rail and provided with a welding hole therein, and a weld formed within said hole. 95

2. The combination with a rail and its support, of a rail anchor comprising an element disposed beneath the rail base to engage said support and another element fitting the rail flange and having a welding hole, and a body of metal within the hole welded to the rail and to the anchor. 100

3. A rail anchor comprising in combination with the rail, an anchoring element overlying the rail flange and provided with a welding hole, and having a member disposed beneath the rail base to engage a single tie, and a weld formed between the rail and anchor within said hole. 105

4. The combination with a rail and an abutment, of an anchor body having a member beneath the rail base and engaging said abutment, and another member engaging over the rail flange and having a welding hole therein, and a body of metal welded to the rail and to the anchor body member within said hole. 110

5. A rail anchor comprising, in combination with the rail, an anchoring element having an abutment engaging member disposed beneath the rail base and another member overlying the rail flange, said element also having a welding hole therein, and a weld formed within said hole. 115

6. A rail anchor comprising, in combination with the rail, an anchoring element having a member disposed beneath the rail base for engagement with the tie or other abutment, and another member overlying the rail flange, said latter member having a 120 125 130

welding hole therein, and a weld formed within said hole.

7. A rail anchor comprising in combination with the rail, a rail clip adapted to embrace the rail flange and having a welding hole therein, and a weld formed within said hole.

8. A rail anchor comprising, in combination with the rail, a rail clip having upper and lower jaws fitting the upper and lower sides respectively of the rail flange and provided with a welding hole therein, and a weld formed within said hole.

9. An anti-creeper for railway rails comprising a weld formed with and on the rail and an anchor member fused with the weld and having a part underlying the rail bottom to engage a cross-tie or ties of the track.

10. The combination with a railway rail and its supporting cross tie, of an anchor having a part underlying the rail bottom and adapted to coöperate with the cross tie to prevent creeping of the rail, and a weld on the rail arranged to hold said anchor in position on the rail.

11. A rail anchor comprising a lower member underlying the rail bottom adapted to engage a cross tie and an upper member adapted to be disposed above the rail flange and provided therein with a welding hole, and a separate body of metal welded to the rail and within said hole.

12. A one piece rail anchor adapted to be welded to the top of a rail flange and comprising a metal bar bent between its ends

to form respectively tie abutting and rail engaging portions, said tie abutting portion underlying the rail bottom.

13. A one piece rail anchor adapted to be welded to the rail flange and bent to form an upper rail engaging portion and a lower depending portion, a part of the depending portion being bent to form a tie engaging abutment underlying the rail bottom.

14. A rail anchor comprising a clip embracing the top and bottom of the rail flange, the upper member of the clip having a welding hole therein, and a bonding weld formed in said hole.

15. An anti-creeper for railway rails comprising a weld rising from the rail, and an anchor member having a bent and perforated portion united to said weld and having a member for engagement with the cross-tie, said latter member underlying the rail bottom.

16. An anti-creeper for railway rails comprising weld metal on the base flange of the rail and an anchor member having a bent and perforated portion united to and fitting said weld metal and having a member for engagement with the cross-tie, said latter member underlying the rail bottom.

In testimony whereof I hereunto affix my signature in the presence of two witnesses.

BENJAMIN WOLHAUPTER.
